P. H. Scheib

Inventor,

Attorney

UNITED STATES PATENT OFFICE.

PETER H. SCHEIB, OF DENVER, COLORADO, ASSIGNOR TO THE DENVER ROCK DRILL MANUFACTURING COMPANY, OF DENVER, COLORADO, A CORPORATION OF DELAWARE.

THROTTLE VALVE.

Application filed December 7, 1920. Serial No. 428,941.

To all whom it may concern:

Be it known that I, PETER H. SCHEIB, a citizen of the United States, residing at Denver, in the county of Denver and State of Colorado, have invented certain new and useful Improvements in Throttle Valves, of which the following is a specification.

The present invention relates more particularly to throttle or controlling valves for rock drills, but may be utilized for other purposes. As is well known, it is the common practice to employ rotary valves having tapered bearing portions. The pressure of the fluid against these valves is in a direction to force the taper portion into engagement with its seat. While this is essential the pressure is often so great as to cause the valve to stick or be operable only under difficulty.

The primary object of the present invention is to provide means whereby the pressure is in great measure relieved, though sufficient is maintained to secure the necessary seating action. As a consequence the bearing is secured in snug condition, and yet is not so tight as to make the operation of the valve difficult.

An embodiment of the invention that is at present considered the preferable one, is illustrated in the accompanying drawings, wherein:—

Figure 1 is a longitudinal sectional view through a portion of a rock drill, showing the improved valve structure,

Figure 2 is a cross sectional view on the line 2—2 of Figure 1,

Figure 3 is a longitudinal sectional view on an enlarged scale through the valve structure.

In the embodiment disclosed, a drill actuated motor is shown generally at 4, and the usual fluid pressure operated feeding means is designated 5. Interposed between the members 4 and 5 is a head block 6 having at one side a valve casing 7 provided with a tapered valve seat 8. A supply passageway 9 leads from the seat to the motor 4, and a passageway 10 also extends from the seat to the fluid pressure operated feeding means 5.

The valve is designated generally by the reference numeral 11, and is tapered to conform to the taper of the seat 8. Mounted

on its smaller end is an exposed operating handle 12 that is located at one end of the valve casing 7. An intake port 13 opens through the larger end and is in communication with lateral ports 14 and 15 that are movable into and out of communication with the passageways 9 and 10 accordingly as the valve 11 is turned by its handle 12. The larger end of the valve is also provided with a reduced extension 16 that is generally cylindrical in form.

A plug 17, threaded into the opposite end of the valve casing 7 to the handle 12, secures in place a nipple 18 to which a motive fluid supply line, as for example a hose, may be connected. The bore 19 of this nipple is in line with the intake port 13 of the valve. The inner end of the plug 17 surrounds the extension 16 of the valve and carries a packing gasket 20 that snugly receives the said extension. This packing gasket is held in place by a retaining collar 21 threaded into the inner end of the plug. The said inner end of the plug is spaced from the shoulder 22 formed on the larger end of the valve, thus producing a chamber 23, and a vent 24 opens from said chamber through the valve casing 7 to atmosphere.

With this structure it will be evident that the pressure of the motive fluid introduced through the nipple 18 operates only against the end surface of the extension 16 and the bottom or closed end wall of the intake port 13, the packing substantially cutting off the passage of the fluid around the extension 16. Inasmuch as there may be and in practice usually is a slight amount of leakage past the packing, the vent 24 permits the escape of the fluid and prevents any building up of pressure against the shoulder 22. It will thus be evident that while there will be pressure against the valve sufficient to hold it in its tapered seat, the amount of this pressure is relatively slight and the valve therefore is easily operable.

From the foregoing, it is thought that the construction, operation and many advantages of the herein described invention will be apparent to those skilled in the art, without further description, and it will be understood that various changes in the size, shape, proportion and minor details of con-

struction may be resorted to without departing from the spirit or sacrificing any of the advantages of the invention.

Having thus fully described my invention, what I claim as new, and desire to secure by Letters Patent, is:—

1. In a structure of the character set forth, the combination with a valve casing, of a tapered valve rotatably mounted in the casing and having an exposed operating handle at its smaller end, means for supplying motive fluid to the casing at the larger end of the valve, and means for relieving a portion of said larger end from the pressure of the motive fluid while retaining the pressure against the remainder.

2. In a structure of the character set forth, the combination with a valve casing, of a tapered valve rotatably mounted in the casing and having an exposed operating handle at its smaller end, means for supplying motive fluid to the casing at the larger end of the valve, means for cutting off the fluid from a portion of the larger end of the valve, and means for allowing the escape of any leakage away from said portion.

3. In a structure of the character set forth, the combination with a valve casing, of a tapered valve rotatably mounted in the casing and having an exposed operating handle at its smaller end and an intake port in its larger end, means for supplying motive fluid to said larger end, a passageway around said larger end, and a vent port from said passageway opening to atmosphere.

4. In a structure of the character set forth, the combination with a valve casing, of a rotary throttle valve therein having an ex-

posed handle at one end and an intake port opening through the opposite end, said latter end having a reduced extension forming a shoulder, a packing element surrounding the extension, a vent port opening between the shoulder and packing element, and means for supplying fluid under pressure to the intake port.

5. In a structure of the character set forth, the combination with a valve casing, of a rotary tapered throttle valve therein having an exposed handle at its smaller end and an intake port opening through the larger end, said latter end having a reduced extension forming a shoulder, a packing element surrounding the extension and spaced from the shoulder forming a chamber, a vent port opening into the chamber, and means for supplying fluid under pressure to the intake port.

6. In a structure of the character set forth, the combination with a valve casing, of a rotary throttle valve therein having an exposed handle at one end and an intake port opening through the opposite end, said latter end having a reduced extension forming a shoulder, a plug in the valve casing surrounding the extension, and packing held by said plug and cooperating with the extension, said valve casing having a vent port between the plug and shoulder.

In testimony whereof, I affix my signature in the presence of two witnesses.

PETER H. SCHEIB.
